UNITED STATES PATENT OFFICE.

THOMAS FRANCIS LILLY, OF MEMPHIS, TENNESSEE.

AEROPLANE FLYING-MACHINE.

1,183,991.

Specification of Letters Patent. Patented May 23, 1916.

Application filed March 24, 1909. Serial No. 485,439.

To all whom it may concern:

Be it known that I, THOMAS F. LILLY, a citizen of the United States, residing at Memphis, in the county of Shelby and State 5 of Tennessee, have invented certain new and useful Improvements in Aeroplane Flying-Machines, of which the following is a specification.

My invention relates to aeroplane flying machines and its object is to provide a device of this class in which angularly adjustable planes so mounted as to swing edge-wise when moving upwardly, are provided as the sustaining and propelling means.

15 My invention is embodied in preferred form in the device illustrated in the accompanying drawings and hereinafter described.

In these drawings, Figure 1 is a side 20 view in elevation of the machine; Fig. 2 a similar view in detail and enlarged, of one set of planes and their carrying member; Fig. 3 is a front view in elevation; Fig. 4 is a top plan view and Fig. 5, a detail of 25 one set of planes and their carrying member with one side of said member removed.

Referring to the drawings illustrating my invention, 1 is a main shaft mounted in bearings 2 on the frame proper 3 of the machine. Fixedly secured to the main shaft 1 are members 4 comprising crossed arms 5 in which are mounted at their outer ends bearings 6. Shafts 7, to which are fixedly secured plane-carrying members 8, are journaled in the bearings 6 on each of the members 4.

To the main shaft 1 is secured a sprocket wheel 9 which in conjunction with a chain 10 passing thereover and over a sprocket 40 wheel 11 carried by shaft 12 at the base of the machine is adapted to revolve the members 4 through the medium of an engine 13. The shaft 12 is driven by a chain 14 engaging sprocket 15.

45 Sprockets 16 are fixed on the shafts 7 which carry the plane-carrying members.

A movable sprocket 17 fits loosely around the main shaft 1. Chains 18 pass over the sprockets 16 and 17 and normally hold the 50 plane-carrying members in the position shown in Fig. 1. A lever 19 is operatively connected to a cam 19^a on the sprocket so that if the sprocket 17 is moved to one position the plane-carrying members will be 55 tilted. It will thus be seen that by providing means for tilting the plane-carrying

members that such members may be raised or lowered to change the angle of the planes. It will also be seen that by means of the loose mounting of the sprocket 17 on the main shaft 1 that such operation of changing the angle of the planes may be effected while the revolving member is in motion.

The plane-carrying members 8 comprise two side-frames 20 which are connected by 65 rods 21. Planes 22 swing on the rods 21 and are journaled thereon at 23.

By means of the sprockets 16 and 17 and chains 18 the plane-carrying members are held in such a position that they will only 70 move in the path of the armed members and while in such path, will be caused to bear down and exert full force of their area.

Upon the revolving of the members 4 with 75 the plane-carrying members thereon, the planes 22 are closed to prevent the escape of air through the member, when the air strikes the bottom of the planes. The rod 21 near the free end of the plane serves as a 80 stop to prevent the planes moving too far upward. But when the air strikes the top of the planes, they will flap open to allow the air to pass through. To prevent the planes opening too wide, cords 24 are provided, so that the planes on their upward motion will strike the air at an angle, whereby the machine is forced forward; while the other planes that are closed will lift or elevate the machine. 90

To facilitate the operation of the lever from the basket or load 25, the movable sprocket 17 is provided with a radial arm rigidly fixed thereto. The lever 27 is pivotally connected to the arm and, adjacent 95 to the basket, is provided with a series of teeth adapted to mesh with the teeth of a segment α . Pressing against the lever at the point where the teeth mesh with the segment, is a spring b which serves to hold 100 the same in mesh. To adjust the planes, the lever is pulled against the spring until the lever and segment teeth are out of mesh, whereupon the lever can be moved vertically. When the desired adjustment is obtained, the lever is released and the spring 105 will hold the teeth in mesh and against displacement.

In operation, the engine by means of chain 14 and sprocket 15 drives shaft 12, 110 which shaft through the medium of chain 10 and sprockets 9 and 11, drives the main

shaft 1, thereby revolving the armed members 4 carrying the plane-carrying members. The machine is raised or elevated by the closed planes coming in contact with the air. 5 While some of the planes are closed the other planes are opened by the force of the air so as to strike the air at an angle which forces the machine forward. As before explained the tilt or angle of the planes can 10 be changed during the operation of the machine from the basket or load.

By means of the opening of the planes, the air which would strike the surface left by the planes when they open is not resisted 15 as is the case if the propellers were parachutes, but such air is allowed to escape.

It is clear that various changes may be made in the device herein described without departing from the principle of my invention. 20

Having thus described my invention, what I claim is:—

1. In a flying machine, a main frame mounted to revolve, means for revolving 25 said main frame, a series of other frames mounted to revolve and carried by said main frame, each of said last mentioned frames having a double series of pivoted planes mounted thereon disposed one series above the other and on each side of the center of the frame, the planes of each series being adapted to fold to closed position and impinge upon the air during the downward movement of the frame carrying them 30 and be swung open by the passage of the air through said frame during the re- 35

mainder of the revolution, one or more of said frames at all times during the revolution having planes impinging upon the air and one or more frames having planes 40 swung open, substantially as set forth.

2. In a flying machine, a revoluble member, shafts journaled thereon, plane-carrying members mounted on the shafts, said members having side frame and rods connecting the same, planes pivoted on rods of said frame, said planes having a member connected thereto and to one of the side frames to limit its swinging movement in one direction, said planes adapted to abut 50 against the adjacent rod to limit its swinging movement in the other direction, a sprocket wheel on each of the said shafts, chains passing thereon, and a lever device for operating the chains and sprocket wheels 55 to change the angle of the plane carrying members, said planes impinging upon the air during part of the revolution of the member to prevent the passage of air through the member and swung open during the remainder of the revolution of the member to permit the passage of air through the member, said revoluble member at all times during its revolution having planes impinging upon the air and planes swung 60 open.

In testimony whereof I have affixed my signature in presence of two witnesses.

THOMAS FRANCIS LILLY.
